(57) **CLAIM**

The ornamental design for a surface pattern of a seam for an absorbent article, substantially as shown and described.

DESCRIPTION

FIG. 1 is a top plan view of a surface pattern of a seam for an absorbent article showing one embodiment of our new design;

FIG. 2 is a top plan view of a surface pattern of a seam for an absorbent article showing a second embodiment of our new design;

FIG. 3 is a top plan view of a surface pattern of a seam for an absorbent article showing a third embodiment of our new design;

FIG. 4 is a top plan view of a surface pattern of a seam for an absorbent article showing a fourth embodiment of our new design;

FIG. 5 is a top plan view of a surface pattern of a seam for an absorbent article showing a fifth embodiment of our new design; and,

FIG. 6 is a top plan view of a surface pattern of a seam for an absorbent article showing a sixth embodiment of our new design.

The broken lines shown in FIGS. 1-6 are for illustrative purposes only and form no part of the claimed design.
